New Device Sanitizes Escalator Handrails While They're in Use | Mental Floss article 2017, <http://mentalfloss.com/article/502821/new-device-sanitizes-escalator-handrails-while-theyr...> site visited Jun. 11, 2019.*

Primary Examiner — John R Yeh

(74) *Attorney, Agent, or Firm* — Saliwanchik, Lloyd & Eisenschenk

(57) **CLAIM**

The ornamental design for a disinfection unit for escalator handrails, as shown and described.

DESCRIPTION

FIG. 1 is a front, right side, perspective view of a disinfection unit for escalator handrails showing my new design; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures represent portions of the disinfection unit for escalator handrails that form no part of the claimed design.

1 Claim, 7 Drawing Sheets
